WINDSHIELD CLEANNER

Filed March 24, 1924

UNITED STATES PATENT OFFICE.

FREDERICK G. FOLBERTH AND WILLIAM M. FOLBERTH, OF CLEVELAND, OHIO, AS-SIGNORS TO TRICO PRODUCTS CORPORATION, OF BUFFALO, NEW YORK, A CORPORATION OF NEW YORK.

WINDSHIELD CLEANER.

Application filed March 24, 1924. Serial No. 701,519.

This invention relates to windshield cleaners and more particularly to vacuum operated cleaners adapted for connection with the intake manifold of an internal combustion engine.

An important object of the invention is to provide an improved cylinder and general motor construction.

A further object of the invention is to provide a simplified and efficient form of valve mechanism.

A further object of the invention is to provide a windshield cleaner as a whole which is adapted to be quickly and easily assembled for operation.

Other objects and advantages of the invention will be apparent during the course of the following description.

In the drawings we have shown one embodiment of the invention. In this showing,

Figure 1 is a perspective view of the assembled windshield cleaner,

Figure 2 is a central vertical transverse sectional view showing the windshield cleaner in position on a windshield,

Figure 3 is a section on line 3—3 of Figure 2,

Figure 4 is a detail sectional view on line 4—4 of Figure 2, and

Figure 5 is a detail perspective view of the valve and operating elements.

Referring to the drawings, the numeral 1 designates a pair of cylinder sections each 35 preferably formed integrally of drawn sheet metal or the like as shown in Figure 3. The cylinders are closed at their outer ends by preferably integral heads 2. The inner edges of the cylinder sections are arranged 40 in end to end relation and contacting with each other as shown at 3 and the inner ends of the cylinders are provided with aligned recesses 4 for a purpose to be described.

The numeral 5 designates a closure plate 45 or central member as a whole provided with a transverse bearing 6 adapted to receive a cleaner shaft 7. The closure plate 5 is provided adjacent opposite ends and upon opposite sides of the shaft 7 with threaded 50 openings 8 adapted to receive screws (not shown) whereby the closure plate may be secured to the frame 9 of a windshield provided with the usual glass 10, as shown in

Figure 2. The outer end of the shaft 7 projects through the windshield frame as shown 55 in Figure 2 and is provided with a cleaner arm 11 secured thereto by a set screw 12 and carrying at its lower end a wiper blade 13 of any desired construction. The shaft 7 projects through the opposite side of the cylinder sections and is provided at its inner end with an operating handle 14.

The ends of the closure plate 5 are provided with curved inner faces adapted to snugly fit against the walls of the cylinder 60 sections 1 as shown in Figure 1 and the lower portion of the cover plate is provided upon its outer face with lugs 15 arranged adjacent opposite ends. The closure plate is further provided with outwardly projecting 70 shoulders 16. The numeral 17 designates a clamping band provided at one end with spaced end portions provided with openings 18 for receiving the lugs 15. The opposite end of the band 17 is provided with a horizontal extension 19 adapted to be arranged adjacent the shoulders 16. Screws 20 pass through the extension 19 and into the shoulder 16 of the cover plate whereby the band may be secured to the cover plate. As 80 shown in Figure 1 the band 17 conforms in curvature to and snugly fits around the inner ends of the cylinder sections 1 to securely hold them in their proper position as shown. While the band frictionally grips 85 the cup-shaped cylinder sections for firmly holding them in place, it is not essential that the joint should be air tight because atmospheric pressure is admitted to the space between the pistons to be referred to. Air 90 may also enter the casing about the shaft 7 and for the purposes of illustration this provision for air admission has been accentuated at 7' in Fig. 2.

The cover plate 5 is provided with a transverse extension 21 extending through the recesses 4 formed in the ends of the cylinder sections 1 and this extension is provided with a preferably machined inner face 22 formed parallel to the axis of the cylinder 100 sections. The cover plate 5 is further provided with an extension 23 which is circular in cross section and forms a continuation of the bearing 6.

A segment gear 24 is secured in any suitable manner to the shaft 7 centrally of the

cylinder sections and preferably contacting with the end of the extension 23 as shown in Figure 2. The segment gear is provided with gear teeth 25 as shown in Figures 2 and 3.

The numeral 26 designates a pair of pistons as a whole comprising disks 27 which may be formed of metal or any other suitable material. A washer 28 is arranged between the disks 27 of each piston and the washers 28 are provided at their outer edges with extensions 29 snugly fitting the inner walls of the cylinders. The numeral 30 designates a connecting bar extending between the pistons and provided with a series of alined openings 31 forming a rack adapted to receive the teeth 25 of the segment gear. The ends of the bar 30 are turned upwardly and inwardly as at 32 and screws 33 secure the elements of each piston together and to the ends 32 of the connecting bar. It will be obvious that the bar 30 forms a rigid connection between the pistons 26 so that they move as a unit during the operation of the device.

The cover plate 5 is provided upon its outer face with a transverse extension 34 as shown in Figures 1, 2 and 3. In its lower portion, the extension is provided with a preferably angularly arranged opening 35 threaded to receive a stem 36 having a knurled operating handle 37 at its lower end. The inner end of the stem 36 is tapered to form a valve 38 adapted to seat against a valve seat 39 formed at the upper end of the opening 35. The valve seat 39 communicates at its upper end with an outwardly and downwardly extending passage 40 drilled through the machined face 22 of the extension 21. A longitudinally extending pipe 41 communicates with the upper end of the opening 35 and the pipe 41 is adapted to be received within one end of a tube (not shown) preferably formed of rubber and connected at its opposite end to the intake manifold of an automobile engine. As shown in Figure 4 a pair of parallel passages 42 arranged transversely of the axis of the cylinder are drilled through the machined face of the extension 21 upon opposite sides of the passage 40 and the outer ends of the passages 42 connect with pipes 43, the opposite ends of which communicate as at 44 with the interior of the outer ends 55 of the cylinder sections.

The numeral 45 designates a cup valve having machined inner edges adapted to seat against the machined face 22 as shown in Figures 2 and 4. The passages 42 are provided in close proximity to the passage 40 so that the cup valve 45 will connect the passage 40 with either of the passages 42 depending upon the position of the cup valve as will be described. The numeral 46 designates a valve shifting lever pivotally con-

nected by a screw 47 with the extension 21 above the shaft 7. The lever 46 has an outwardly curved intermediate portion 48 extending around the sleeve 23 and is provided in its lower end with an opening 49 adapted to receive an axial stem 50 formed on the valve 45. The lower end of the lever 46 is provided with a transverse extension 51 terminating in an outer up-turned end 52 having an opening 53 formed therein for a purpose to be described.

The under side of the extension 23 is provided with lateral extensions 54 and a groove 55 is formed in the lower portion of the extension 23 and the extensions 54. The groove 55 is preferably formed parallel to the axis of the cylinders and is adapted to receive a slide 56 shown in detail in Figure 5. The central portion of the slide 56 is relatively narrow as shown and the ends of the member are provided with upwardly extending extensions 57 adapted to contact with the ends of the extensions 54 to limit the longitudinal movement of the slide. The lower central portion of the slide 56 is provided with an opening 58 adapted to receive the upper end of a compression spring 59, the lower end of which is received in the opening 53 of the valve shifting lever. As shown in Figure 2, the slide 56 is preferably arranged slightly outwardly of the bar 30 so as to contact with the inner disk 27 of either piston. It will be obvious, however, that the ends of the slide may contact with the up-turned ends 32 of the bar 30 if desired in which case the ends of the slide 56 would be shortened a distance equal to the thickness of the end 32. The spring 59 is the sole means of connection between the valve carrier or shifter 46 and the spring positioning member or slide 56. By reason of the fact that it is a compression type of spring it not only pushes upwardly on the slide to hold it in its guiding groove 55 but it also acts to push downwardly on the outstanding part 52 and thereby urges the valve 45 into firm contact with the valve seat 22. This firm seating is accentuated or augmented by giving the spring a slight inclination, as depicted in Fig. 2.

As shown in Figure 2, the lower portion of the extension 21 is provided with a lateral extension 60 which may be formed integral with the extension 21 or may be in the form of a screw or pin mounted in the extension. The extension 60 is arranged in vertical alinement with the passage 40 and is adapted to contact with depending portions 61 on the lever 46 as shown in Figure 3 to limit the swinging movement of the lever 46 in either direction.

The operation of the device is as follows:

With the pipe 41 in communication with suitable suction producing means such as

the intake manifold of an engine, the knob 37 is revolved to unseat the valve 38. The vacuum will then be communicated to the interior of the cup valve 45 as will be obvious. The cup valve will be in communication with either pipe 43 which in turn will communicate with one of the cylinders and atmospheric pressure in the other cylinder will cause longitudinal movement of the 10 pistons. The rack 31 will oscillate the segment gear 24 thus swinging the cleaner arm 11 and cleaner blade 13. As the pistons approach the end of the stroke the slide 56 will be moved by contact with one of the 15 pistons until the upper end of the spring 59 passes beyond the point where it is in vertical alignment with the lower end of the spring. This action will snap the lower end of the lever 46 in the opposite direction 20 thus establishing communication between the source of vacuum and the opposite end of the cylinder. This action is repeated until it is desired to stop the operation of the cleaner whereupon the valve 38 may be 25 closed as will be understood. The handle 14 is provided for mere convenience in case the automobile is left standing in a snow fall or the like whereby the blade 13 will stick in one position. Operation of the handle 14 will loosen the blade so that normal operation of the cleaner may be resumed.

It will be apparent that the groove 55 acts as a slide bearing for the slide 56 and since the bottom of the bearing is open the 30 slide may be easily inserted therein. The spring 59 is a compression spring as stated, and when the device is assembled the spring is adapted to seat the slide within its bearing and maintain it in sliding engagement 35 therewith during the normal operation of the device. When assembling the valve mechanism the lever 46 is attached to the extension 21 by means of the screw 47. The lower end of the spring is then inserted in 40 the opening 53 and the upper end within the opening 58. The slide 56 is then moved downwardly against the tension of the spring and inwardly until it is in vertical alignment with the groove 55. The slide 56 45 is then allowed to move upwardly under the tension of the spring until it is properly seated in the groove. It has been found that the device may be assembled as described in a very short space of time and 50 the parts are not likely to derangement in 55 operation.

It is to be understood that the form of our invention herewith shown and described 60 is to be taken as a preferred example of the same and that various changes in the shape, size, and arrangement of parts may be resorted to without departing from the spirit of the invention or the scope of the subjoined claims.

Having described our invention, we claim:

1. In a windshield cleaner comprising a casing, a movable element arranged in said casing and adapted to be operated by fluid pressure, and valve mechanism to alternately connect said casing upon opposite sides of 70 said movable element to a source of fluid pressure, said valve mechanism comprising a pivoted member, means for limiting the movement of said member, a valve carried by said pivoted member, a guide on the casing, a slidable member arranged in said guide and adapted to be actuated by said movable element, said slidable member being provided at its ends with projecting portions adapted to engage the ends of said 75 guide to limit the movement of said slidable member, and a compression spring connected between said pivoted member and said slidable member and positionable by the latter for moving said pivoted member back and forth, said spring acting to yieldably hold the slidable member in its guide.

2. In a windshield cleaner comprising a casing, a movable element arranged in said casing and adapted to be operated by fluid 90 pressure, and valve mechanism to alternately connect said casing on opposite sides of said movable element to a source of fluid pressure, said valve mechanism comprising a pivoted member, means for limiting the 95 movement of said member, a valve carried by said pivoted member, an open slide bearing, a slidable member arranged in said bearing and adapted to be actuated by said movable element, means for limiting the 100 movement of said slidable member, and a compression spring connected between said pivoted member and said slidable member and positionable by the latter to move the 105 pivoted member, said spring acting to seat said slidable member in said bearing.

3. In a windshield cleaner comprising a casing, a movable element arranged in said casing and adapted to be operated by fluid pressure, a shaft extending transversely 110 through said casing and adapted to be actuated by said movable element, and valve mechanism to alternately connect said casing on opposite sides of said movable element to a source of fluid pressure, said valve 115 mechanism comprising a valve seat, a pivoted member, a valve carried at one side of and by the pivoted member for engaging said seat, an open bearing, a slidable member arranged in said bearing and provided 120 upon opposite ends with projecting portions adapted to engage the ends of said bearing to limit the movement of said slidable member, said slidable member being movable by 125 said movable element, and a compression spring connected between said pivoted and slidable members and acting to shift the pivoted member back and forth, said spring also acting to seat said slidable member in 130 said bearing with said bearing, and being

arranged on the opposite side of said pivoted member to urge the valve to its seat, said spring and said slideable member being arranged wholly to one side of said shaft.

- 5 4. In a windshield cleaner comprising a casing, a movable element arranged in said casing and adapted to be operated by fluid pressure, a closure plate arranged substantially centrally of said casing and provided with a transverse bearing, a shaft mounted in said bearing, and valve mechanism to alternately connect said casing on opposite sides of said movable element to a source of fluid pressure, said valve mechanism comprising a member pivotally connected to said closure plate above said bearing and extending therebelow, means for limiting the movement of said member, a valve carried by said member, a slideable member slidably supported by said closure plate beneath said bearing and adapted to be actuated by said movable element, means for limiting the movement of said slideable member, and a spring connected between said slideable member and the lower end of said pivotal member for shifting the latter when said slideable member has properly positioned the spring.

5. A device constructed in accordance with claim 4 wherein said bearing is provided with an integral slide bearing arranged therebelow to receive said slideable member.

6. A device constructed in accordance with claim 4 wherein said bearing is provided with an integral slide bearing arranged therebelow to receive said slideable member, the limiting means for said slideable member being adapted to engage said slide bearing.

40 7. In a fluid pressure motor for windshield cleaners, a casing having an opening in its side, a supporting member therefor having an enlargement extending inwardly through the casing opening, said enlargement having a valve face provided with a suction port and spaced fluid ports, the fluid ports being connected to the respective ends of the casing, a valve operable over the face of said enlargement for connecting the suction port alternately with each fluid port, a part on said enlargement overhanging the ports thereof and provided with a guide extending lengthwise of the casing, a valve carrier pivoted on said enlargement above the ports thereof, a spring for shifting the valve carrier back and forth and connected at one end to the carrier, a spring positioning member slideable along the guide lengthwise of the casing and connected to the opposite end of the spring, a piston operable in the casing and adapted to shift the positioning member back and forth along its guide and a shaft operable by the piston.

8. In a fluid pressure motor for windshield cleaners, a snap-action valve mecha-

nism comprising a casing part having a valve seat and an overhanging bearing member, said bearing member having a guide extending substantially parallel to the face of the valve seat, a valve on the seat, a carrier pivoted on the casing part for moving the valve on its seat, a spring positioning member, and a spring compressed between and connected to the positioning member and the carrier for shifting the latter and its valve back and forth, said positioning member being movable back and forth along the guide by a movable part of the motor for positioning the spring to opposite sides of its point of connection with the carrier.

9. In a fluid pressure motor for windshield cleaners, a snap-action valve mechanism comprising a casing part having a valve seat and a member extending outwardly beyond the seat, said member having a guide groove, a valve, a carrier pivoted to said casing part for moving the valve over the valve seat, a spring positioning member slidably disposed in the guide groove of said member for limited movement and operable by a moving part of the motor, a spring compressed between the carrier and said positioning member for shifting the carrier and its valve when properly positioned by the positioning member, said spring serving to retain the positioning member in the guide groove of said member.

10. In a fluid pressure motor for windshield cleaners, a snap-action valve mechanism comprising a casing part having a valve seat and a projecting bearing sleeve, the sleeve being formed with a transverse groove on its side adjacent the valve seat, a valve on the valve seat, a carrier for shifting the valve on its seat, a positioning member slideable in the groove of said sleeve by a movable part of the motor, and a spring compressed between the carrier and the positioning member and positionable by the latter to effect a shift of the carrier and its valve.

11. In a fluid pressure motor for windshield cleaners, a snap-action valve mechanism comprising a casing part having a valve seat and an overhanging projecting bearing sleeve having a transverse guide, a positioning member slideable in the guide of said sleeve and having parts engaging with the sleeve to limit its sliding movement, said member being slideable by a moving part of the motor, a valve movable over the valve seat, a carrier pivoted on the casing part for moving the valve on its seat and having a part extending outwardly beneath the positioning member, and a spring compressed between said carrier part and the overlying positioning member for shifting the carrier when properly positioned by said positioning member.

12. In a fluid pressure motor for windshield cleaners, a snap-action valve mechanism comprising a casing part having a valve seat and an overhanging projecting sleeve, said sleeve having on its underside opposite lateral extensions and a downwardly opening transverse groove extending through said lateral extensions and said sleeve, a positioning member inserted upwardly into the groove and slideable therein by a moving part of the motor, said positioning member having stop portions for limiting the sliding movement in the groove, and said lateral extensions of the sleeve providing a long bearing for the positioning member, a valve on the valve seat, a carrier pivotally supported by said casing part for moving said valve on its seat, said carrier having a part extended beneath the sleeve, and a spring compressed between said carrier part and said positioning member and positionable by the latter for shifting the carrier, said spring acting to hold the positioning member in its groove.
13. In a fluid pressure motor for windshield cleaners, a snap action valve mechanism comprising a casing part having a valve seat, a valve movable on the seat, a carrier for the valve supporting the latter on one side, a slideable positioning member mounted at the opposite side of said carrier and movable by a movable part of the motor substantially parallel to the direction of movement of said carrier, and a spring interposed between said positioning member and said carrier and acting on said carrier in a dual capacity to urge the valve to its seat and for shifting the carrier when properly positioned by said positioning member.
14. In a fluid pressure motor for windshield cleaners, a snap action valve mechanism comprising a casing part having a valve seat and an overhanging support provided with a transverse guide, a positioning member slideable in the guide for limited movement by a moving part of the motor, a valve movable over the valve seat, a carrier pivoted to the casing part and supporting the valve at one side and having a part extending to the opposite side, and a spring compressed between the carrier part and the positioning member for shifting the carrier when properly positioned by said member, said positioning member being offset further from said carrier than said carrier part whereby said spring will be disposed at an angle for urging the valve to its seat.

In testimony whereof, we affix our signatures.

CERTIFICATE OF CORRECTION.

Patent No. 1,670,680.

Granted May 22, 1928, to

FREDERICK G. FOLBERTH ET AL.

It is hereby certified that error appears in the printed specification of the above numbered patent requiring correction as follows: Page 3, line 102, claim 2, for the misspelled word "compresion" read "compression"; same page, line 130, claim 3, strike out the words "with said bearing", and page 4, line 2, claim 3, after the word "seat" insert the words "said bearing with"; and that the said Letters Patent should be read with these corrections therein that the same may conform to the record of the case in the Patent Office.

Signed and sealed this 19th day of June, A. D. 1928.

M. J. Moore,
Acting Commissioner of Patents.

12. In a fluid pressure motor for windshield cleaners, a snap-action valve mechanism comprising a casing part having a valve seat and an overhanging projecting sleeve, said sleeve having on its underside opposite lateral extensions and a downwardly opening transverse groove extending through said lateral extensions and said sleeve, a positioning member inserted upwardly into the groove and slideable therein by a moving part of the motor, said positioning member having stop portions for limiting the sliding movement in the groove, and said lateral extensions of the sleeve providing a long bearing for the positioning member, a valve on the valve seat, a carrier pivotally supported by said casing part for moving said valve on its seat, said carrier having a part extended beneath the sleeve, and a spring compressed between said carrier part and said positioning member and positionable by the latter for shifting the carrier, said spring acting to hold the positioning member in its groove.
13. In a fluid pressure motor for windshield cleaners, a snap action valve mechanism comprising a casing part having a valve seat, a valve movable on the seat, a carrier for the valve supporting the latter on one side, a slideable positioning member mounted at the opposite side of said carrier and movable by a movable part of the motor substantially parallel to the direction of movement of said carrier, and a spring interposed between said positioning member and said carrier and acting on said carrier in a dual capacity to urge the valve to its seat and for shifting the carrier when properly positioned by said positioning member.
14. In a fluid pressure motor for windshield cleaners, a snap action valve mechanism comprising a casing part having a valve seat and an overhanging support provided with a transverse guide, a positioning member slideable in the guide for limited movement by a moving part of the motor, a valve movable over the valve seat, a carrier pivoted to the casing part and supporting the valve at one side and having a part extending to the opposite side, and a spring compressed between the carrier part and the positioning member for shifting the carrier when properly positioned by said member, said positioning member being offset further from said carrier than said carrier part whereby said spring will be disposed at an angle for urging the valve to its seat.

In testimony whereof, we affix our signatures.
